UNITED STATES PATENT OFFICE.

JOHN J. BENTZ, OF BROOKLYN, NEW YORK.

NON-REFILLABLE BOTTLE.

SPECIFICATION forming part of Letters Patent No. 708,802, dated September 2, 1902.

Application filed March 27, 1902. Serial No. 100,247. (No model.)

To all whom it may concern:

Be it known that I, JOHN J. BENTZ, a citizen of the United States, and a resident of the city of New York, borough of Brooklyn, in the 5 county of Kings and State of New York, have invented a new and Improved Non-Refillable Bottle, of which the following is a full, clear, and exact description.

This invention relates to a means for preventing bottles from being filled after their 10 original contents have been withdrawn.

This specification is an exact description of one example of my invention, while the claims define the actual scope thereof.

15 Reference is to be had to the accompanying drawings, forming a part of this specification, in which similar characters of reference indicate corresponding parts in all the views.

Figure 1 is a sectional view showing the 20 bottle in upright position. Fig. 2 is a similar view showing the bottle tilted. Fig. 3 is a section on the line 3 3 of Fig. 1. Fig. 4 is a perspective view of the plunger-valve, and Fig. 5 is a similar view of the inverted cup in 25 which the cylinder-valve works.

The neck *a* of the bottle tapers slightly toward the body *b* and has at its upper end a plug *c*, of glass or the like, securely and immovably fitted therein. This plug *c* has a 30 centrally-located orifice *c'*, through which the liquid is drawn off from the bottle. This orifice may, if desired, be closed by a temporary cork, or any other desired form of closure may be employed, such cork or closure being 35 adapted to be withdrawn when the contents of the bottle are to be used. Secured rigidly by cementing or otherwise within the tapered neck of the bottle is a correspondingly-tapered cup or sleeve *d*, the top *d'* of which is 40 perforated, as shown, and the bottom of which is open. Within the inverted cup *d* is the plunger-valve *e*, which comprises a body portion with exterior grooves *e'* running longitudinally along it, and at its lower end the plunger-valve has the valve proper, *e''*, in the form 45 of a rounding knob. This valve proper coacts with a rubber or other flexible tube *f*, forming a valve-seat and secured within a centrally-orificed plug *g*, of cork or like material. 50 This plug is secured rigidly and permanently in the lower end of the neck of the bottle.

When the bottle is upright, the plunger-

valve *e* falls to its seat, and it will be impossible to pour liquid into the bottle; but when the bottle is tilted, as shown in Fig. 2, the plunger 55 falls down against the perforated bottom of the cup *d*, and the valve-tube *f* is opened, thus allowing the liquid to pass freely through this tube, through the grooves *e'* of the plunger *e*, and out by way of the perforated top 60 *d'* of the cup *d* and the orifice *c'* of the plug *c*. In assembling the various parts the plug *g* is first wedged down tightly in the tapered neck *a*, the taper permitting the cork plug to be securely forced into place. Then the plunger 65 *e* is placed in position, and the cup *d* is introduced into the tapered neck and cemented or otherwise secured in place, thus confining the plunger *e* to movement within the proper limits. Finally the glass plug *c* is placed and 70 secured in position.

Various changes in the form and details of my invention may be resorted to at will without departing from the spirit of my invention. Hence I consider myself entitled to all forms 75 of the invention as may lie within the intent of my claims.

Having thus described my invention, I claim as new and desire to secure by Letters Patent—

1. A non-refillable bottle, comprising the combination with the bottle-neck, of a centrally-orificed plug secured in the lower portion thereof, a flexible tube held in the orifice of the plug, a plunger-valve working with 85 the tube, an inverted cup inclosing the plunger-valve and perforated to permit the passage of the liquid therethrough, said plunger-valve having a longitudinal passage for the liquid, and an orificed end plug secured in the outer portion of the neck of the bottle.

2. A non-refillable bottle, comprising the combination with the bottle-neck, of a centrally-orificed plug secured in the lower portion 95 thereof, a flexible tube held in the orifice of the plug, a plunger-valve working with the tube, an inverted cup inclosing the plunger-valve and perforated to permit the passage of the liquid therethrough, said 100 plunger-valve having a longitudinal passage for the liquid, and an orificed end plug secured in the outer portion of the neck of the bottle, the neck of the bottle being tapered

downward toward the body and the said inverted cup being correspondingly tapered.

3. A non-refillable bottle, comprising the combination with the neck of a bottle, of a 5 plug secured in the lower portion thereof and having a central orifice, a yielding tube fitted in said orifice and forming a valve-seat, an inverted cup having perforations in its upper portion, said cup being secured in the neck 10 of the bottle above the said plug, a plunger-valve mounted in the cup and having a longitudinal passage for the liquid, and a glass or like plug secured permanently in the outer portion of the neck and having a central orifice 15 for the passage of the liquid.
4. A non-refillable bottle, comprising the

combination with the bottle-neck, of an orificed plug secured in the lower portion thereof, means held by the plug and constituting a valve-seat, a plunger-valve working with the 20 said means constituting the valve-seat, and an inverted cup inclosing the plunger-valve and perforated to permit the passage of the liquid therethrough, said plunger-valve having a longitudinal passage for the liquid. 25

In testimony whereof I have signed my name to this specification in the presence of two subscribing witnesses.

JOHN J. BENTZ.
